Attorney

UNITED STATES PATENT OFFICE.

ROGER W. GRISWOLD, OF ERIE, PENNSYLVANIA, ASSIGNOR TO GRISWOLD MANUFACTURING COMPANY, OF ERIE, PENNSYLVANIA, A CORPORATION OF PENNSYLVANIA.

HOT-PLATE.

1,179,716.

Specification of Letters Patent. Patented Apr. 18, 1916.

Application filed October 30, 1915. Serial No. 58,753.

To all whom it may concern:

Be it known that I, ROGER W. GRISWOLD, a citizen of the United States, residing at Erie, in the county of Erie and State of Pennsylvania, have invented new and useful Improvements in Hot-Plates, of which the following is a specification.

This invention relates to hot plates and consists in certain improvements in the construction thereof as will be hereinafter fully described and pointed out in the claims.

The object of the invention is to simplify the burner support and valve connection with the gas supply pipe.

15 The invention is illustrated in the accompanying drawings as follows:—

Figure 1 shows a plan view of a part of the hot plate. Fig. 2 a section on the line 2—2 in Fig. 1. Fig. 3 a front elevation 20 of a part of the plate.

1 marks the plate frame, 2 the burner opening, 3 the grid on the burner opening, 4 the gas pipe supporting projection extending from the front of the frame, 5 the 25 gas pipe which ordinarily extends along the front of the stove, 6 the hose connection for the gas pipe, 7 the burner, 8 an extension on the burner, 9 a pocket extending from the frame on which the extension 8 30 rests, 10 a mixer extension on the burner extending toward the front of the plate and 11 the mixer. These parts are in a general way of common construction.

The mixer 11 has an opening 12 in its 35 front face which slips over a projection 13 on the valve 14. The valve 14 has an upwardly extending screw-threaded portion 15 which is screwed into the screw-threaded opening in the bottom of the pipe 5. While 40 this method of supporting the front of the burner and of securing the valve to the gas pipe is a simple and inexpensive one it is objectionable because of the tendency of the valve to be knocked out of alignment with the mixer and where this happens the 45 gas jet 13° from the valve to the burner is moved out of alignment with the mixer and prevents a proper functioning of the mixer

and jet so that there is an imperfect mixture delivered to the burner. The advantage of the simplicity of this construction is utilized in the present invention and the valve 14 is locked against turning relatively to the pipe 5 thus obviating the objection that would otherwise be present. The valve 55 has a forwardly extending screw-threaded portion 16. This extends from the shoulder 17 on the valve body. A plate 18 is slipped on the extension 16 and clamped against the shoulder 17 by means of a nut 19 60 on the extension 16. This plate abuts the face of the pipe 5 and thus securely locks the valve 14 against turning in the pipe 5.

The usual gland 20 is screwed on to the extension 16 and the valve is operated from 65 a handle 21 in the ordinary manner.

What I claim as new is:—

1. In a hot plate, the combination of a plate frame; a gas supply pipe secured to the frame; a valve having a screw connection with said pipe; means for locking the valve against turning relatively to said pipe; and a burner having a mixer extension into which the valve leads and directs the gas jet in alignment with the mixer. 75

2. In a hot plate, the combination of a plate frame; a gas supply pipe secured to the frame; a valve having a screw connection with said pipe and having a screw-threaded extension thereon; a plate secured 80 on said screw-threaded extension and abutting said pipe for locking said valve against turning relatively to said pipe; and a burner having a mixer extension into which the valve leads and directs the gas jet in alignment with the mixer. 85

3. In a hot plate, the combination of a plate frame; a gas supply pipe secured to the frame; a valve having a screw connection with said pipe, said valve having a 90 screw-threaded extension thereon; a plate arranged on said extension and said pipe for locking the valve against turning relatively to said pipe; a nut on said extension clamping said plate on said valve; and a burner 95 having a mixer extension into which the

valve leads and directs the fuel jet into alignment with the mixer.

4. In a hot plate, the combination of a plate frame; a gas supply pipe secured to the frame; a valve having a screw connection with said pipe; means for locking the valve against turning relatively to said

pipe; and a burner having a mixer extension into which the valve leads, said valve supporting the front portion of the burner. ¹⁰

In testimony whereof I have hereunto set my hand.

ROGER W. GRISWOLD.
